DESIGN FOR A BOTTLE

William J. Latchford, Jr., Los Angeles, Calif., assignor to Nesbitt Fruit Products, Inc., Los Angeles, Calif., a corporation of California

Application December 28, 1938, Serial No. 82,015

Term of patent 14 years

To all whom it may concern:

Be it known that I, William J. Latchford, Jr., a citizen of the United States, residing at Los Angeles, in the county of Los Angeles and State of California, have invented a new, original, and ornamental Design for a Bottle, of which the following is a specification, reference being had to the accompanying drawing, forming part thereof.

I claim:

The ornamental design for a bottle, as shown.
